US0D1036676S

(12) **United States Design Patent** (10) **Patent No.:** **US D1,036,676 S**
(45) **Date of Patent:** **** Jul. 23, 2024**

(54) **WEARABLE MEDICAL MONITORING DEVICE**

(71) Applicant: **DexCom, Inc.**, San Diego, CA (US)

(72) Inventors: **John Charles Barry**, San Diego, CA (US); **Young Woo Lee**, San Diego, CA (US); **David A. Keller**, Encinitas, CA (US); **Louise Emma van den Heuvel**, Somerville, MA (US); **Carol Wood Sutherland**, Somerville, MA (US); **John Stanley Hayes**, San Diego, CA (US)

(73) Assignee: **DexCom, Inc.**, San Diego, CA (US)

(**) Term: **15 Years**

(21) Appl. No.: **29/796,523**

(22) Filed: **Jun. 24, 2021**

Related U.S. Application Data

(60) Continuation of application No. 29/717,217, filed on Dec. 16, 2019, now Pat. No. Des. 926,325, which is a division of application No. 29/654,373, filed on Jun. 22, 2018, now Pat. No. Des. 870,291, which is a continuation-in-part of application No. 16/016,354, filed on Jun. 22, 2018, now Pat. No. 10,863,944.
